UNITED STATES PATENT OFFICE.

SIGMUND WEIL AND GEORGE GRIER WATERS, OF ATLANTA, GEORGIA.

STOCK-DISPLAY CABINET.

1,114,080.

Specification of Letters Patent.

Patented Oct. 20, 1914.

Application filed December 22, 1913. Serial No. 808,195.

To all whom it may concern:

Be it known that we, SIGMUND WEIL and GEORGE GRIER WATERS, citizens of the United States, residing at Atlanta, in the county of Fulton and State of Georgia, have invented certain new and useful Improvements in Stock-Display Cabinets, of which the following is a specification.

Our invention relates to improvements in stock and display cabinets, and is particularly designed for the purpose of producing a useful and attractive piece of store furniture, as will be described.

The primary object of our invention is to improve the construction of cabinets for the display of merchandise in stores and other places, in certain particulars, such as increasing the space for exhibiting the merchandise contained in the cabinet by providing display panels at the interior of the cabinet doors, increasing the capacity of the cabinet by arranging the receptacles therein in the best manner to occupy the space in the cabinet, and to enhance the accessibility of the cabinet by providing doors at numerous parts of the cabinet, and also to provide improved means whereby the interior of the cabinet may be adjusted for use in connection with different sized units, as display trays.

The invention consists in certain novel combinations and arrangements of parts as will be hereinafter more fully pointed out.

In the accompanying drawings we have illustrated one complete example of the physical embodiment of our invention constructed according to the best mode we have so far devised for the practical applications of the principles of our invention, and in which we have illustrated a portable rotary cabinet.

Figure 1 is a side elevation of a cabinet constructed according to and embodying the principles of our invention, a portion of the base of the cabinet being broken away to illustrate the wheeled supports for the cabinet. Fig. 2 is a plan view of one of the trays, showing in section the four posts which support the trays within the cabinet. Fig. 3 is a sectional view of Fig. 2, on line 3-3. Fig. 4 is a fragmentary vertical sectional view showing one of the upper corners of the cabinet, and one of the lower corners in its relation thereto, and also

showing the hinged lid of the cabinet. Fig. 5 is a horizontal sectional view showing a corner of the cabinet, one of the supporting posts in section, and a corner portion of one of the supporting shelves. Fig. 6 is a perspective detail view of a handle or pull member which might be used on the trays. Fig. 7 is a perspective view showing a plurality of boxes supported upon the adjustable shelf. Fig. 8 shows the adjustable shelf in its modified form. Fig. 9 shows the supporting cross bars used in connection with the modified adjustable shelf.

In the preferred embodiment of our invention as shown in Fig. 1, we have illustrated the cabinet as comprising the posts 1 at the corners of the cabinet which are supported from the base 2, and the latter forms a cover for a boxing 3 which includes the frame 4 supported on the rotary wheeled frame 5 having the rollers 6. The cabinet is supported upon the frame 4 to revolve with relation to the frame 5, and the supporting rollers 6 in the frame 5 provide means by which the cabinet may be bodily moved with facility when desired.

The cabinet comprises four doors each indicated by the numerals 7, and one being located at each of the four sides of the cabinet. These doors are hinged to the posts 1 at 8-8, and are provided with fastenings 9 of suitable construction. All of the doors are adapted to swing from left to right in opening, and a display panel 10 is hinged at 11 to the inner side of each door 7, and this hinged panel is adapted to swing from right to left when the cabinet door 7 is open on its hinge 8. The hinged panels at the interior of each door 7 may be composed of suitable material as metal, wood, or glass, but in the drawings we have illustrated the panel as composed of glass located just within the glass panel 12 of each door 7.

In Figs. 4 and 5 it will be seen that these display shelves 13 are supported adjacent to the outer face of each panel 10. These display shelves are adapted to support merchandise and stock of different character, and each shelf is provided with a slotted lug 14 adapted to pass over a headed pin 15. The headed pins are secured in perforations in a metallic strap 17, which extends from the top to the bottom, in the center of the panel, and the strap is secured in the top and

bottom strips 19 (see Fig. 4). These display shelves may be of any suitable number and are located just within the glass panel 12 of the door 7, so that the merchandise or stock displayed upon the shelves is in full sight of the observer from outside the cabinet. The panels 10 are preferably in the form of mirrors to render them more attractive and artistic in appearance, but if desired the panels may be of wood, glass, or other material and in which case the display fixtures may be secured thereto in simple manner as will be understood. The glass panel 10 is surrounded by strips 19, and as will be seen in Fig. 5, the hinge 11 is attached to one of these strips. The lid 20 of the cabinet is hinged at 21 to the top frame 22, and the lid also has a glass panel 23 through which the contents of a top tray 24 may be inspected. This top tray 24 is supported upon one of a series of shelves 25 that are adjustably fixed within the interior of the cabinet.

As clearly seen in Figs. 2 and 3 the adjustable shelf 25 is rectangular in shape having an open center and at each corner is provided with a slotted lug 26. There are a number of these shelves 25 located within the cabinet to support a series of trays, one of which is indicated at 27 in Figs. 2 and 3. The shelves are adjustably supported upon four posts 28, one of which is located in each of the four corners of the cabinet, and fixed at its upper end in a bracket 29, 35 and at its lower end in a metal base 30 secured in the base 2 of the cabinet. Each of these posts 28 is fixed with relation to the cabinet, and each of the posts is threaded with screw threads throughout its entire length. These upright posts pass through the slotted lugs 26 of the shelves, and by means of an upper nut 31 and a lower nut 32, each shelf 25 may be clamped on the posts in a desired position. It will be understood that there are a pair of these nuts 31-32 on each post, at each corner of each shelf, and by means of these clamped nuts it will be evident that the shelves may be adjusted most minutely in order to secure the proper altitude of the adjustable shelves. In this manner the shelves may be adapted for use in connection with trays 27 of varying heights, so that the cabinet is capable of using different shapes or sizes of trays or receptacles for different characters of merchandise. Thus, in Figs. 2 and 3, the trays 27 are shown as comprising four compartments A, A, A, A, in which different sizes or grades or qualities of merchandise may be contained.

The adjustable shelves may be detached from their supporting posts with facility by withdrawing the nuts 31-32 from the shelf at its corner so that the shelf may be tilted with relation to the horizontal, and

the slotted lugs withdrawn from the posts as will be understood, and they may be replaced by reversing this process.

Each tray 27 comprises a metallic frame which includes a bottom 33, the lower side bars 34, and the upper side bars 35. At each corner of the frame a post 36 is provided and midway between each corner an intermediate post 37 is formed. A central post 38 is provided at its lower end with a bolt 39 and nut 40 by means of which the post is fixed in the bottom 33 of the tray. The post is rigid with the tray and is adapted to support the inner ends of the series of partitions 40' which serve to divide the tray into compartments A, A, A, A. The sides of the tray are made up of panels 41, and these panels like the partitions 40' are preferably composed of glass having their edges located in grooves formed in the corner and intermediate posts of the frame. The inner edges of the partitions 40' are also located in vertical grooves formed in the central post 38, as will be plainly seen in Fig. 2. It will be understood that these trays 27 may be made of various forms and of suitable material, and we do not wish to be limited to the shape of the trays shown in the drawings, nor to the metallic frame and glass sides and partitions, as set forth in the specification.

In Fig. 6 we have illustrated a handle 41', which may be used as a pull piece for the trays, and one or more of these handles may be attached at each of the four sides of the tray.

As before stated, the tray 24 is accessible by opening the lid 20 of the cabinet. The trays 27 located within the cabinet are accessible through any one of the four side doors, and it will be understood that the trays may be withdrawn from the cabinet between the lock nuts 31, 32 at the corners of the supporting shelf.

In the modified form shown in Figs. 7, 8, and 9, a plurality of boxes 50 are used in the place of the single drawer with the separate compartments. These boxes 50 are supported upon the adjustable shelf 25' and on the integral cross bars 51. The cross bars 51 are provided with upwardly projecting flanges 52, and the bars at their ends are adapted to seat in diametrically arranged notches 53 cut in the inner edge of the open adjustable shelf 25'. Additional notches 54 are provided in the adjustable shelf, by means of which other cross bars may be utilized in connection with the adjustable shelf, to adapt the modified form for other shapes and sizes of boxes. At the corners of the adjustable shelf we provide perforated lugs 55 to take the place of the slotted lugs 26 in the previous form of the invention shown. In some instances these lugs 55 are preferable, and we contemplate using that form of lug when desired.

From the above description taken in connection with the drawings it is evident that we have provided a stock and display cabinet which fulfills the purposes set forth as the 5 objects of our invention.

Having thus fully described our invention what we claim as new and desire to secure by Letters Patent, is:—

1. The combination in a display cabinet 10 having corner posts and hinged glass doors between pairs of posts, of a series of supporting posts and a plurality of independently adjustable shelves thereon, each of said shelves having an outwardly projected 15 corner lug slotted and embracing a post, and means for securing said lugs in adjusted position with relation to the supporting posts.

2. The combination in a display cabinet 20 having four corner posts and hinged doors between the posts, a threaded post adjacent each corner post, a supporting post having

projected slotted corner lugs surrounding the threaded posts, and clamp nuts on each threaded post for supporting the shelf in adjusted position.

25

3. The combination with a display cabinet having four corner posts and hinged doors between said posts, an upright threaded post adjacent each corner post, a series of supporting panels each having corner lugs projecting therefrom and slotted to embrace a threaded post, an upper and a lower clamp nut for each lug, and a tray supported upon each shelf.

30

In testimony whereof we affix our signatures in presence of two witnesses.
